SPLIT SOCKETS AND WRENCHES FOR USE THEREWITH

Ernest E. Cook, Rte. 4, Box 234, Port Orchard, Wash.
Filed Jan. 18, 1960, Ser. No. 3,119
2 Claims. (Cl. 81—121)

This present invention relates to the general art of socket wrenches and more particularly to a socket that is made in two coacting halves which are held together, on a nut to be worked, by a special wrench which engages the split socket so as to hold it in a true circle and to then provide peripheral engagement means so that the socket can be manually driven to loosen or tighten a nut, particularly on a long bolt or rod.

In many mechanical operations it is necessary to turn nuts that are threaded onto long bolts or rods and which preclude the use of the usual socket wrench. In some instances the rods on which the bolts are threaded may have their ends so secured that it is impossible to slip the conventional open bore sockets along the rods to engage the nuts that are difficult or even impossible to engage by any form of open end wrench. There are other circumstances where the bolt to which the nut is threaded may have an end that stands up above the nut for a distance, making it impossible for the socket to be placed down low enough to operatively engage the nut. There are many times when it is very desirable to engage a finished nut on a piece of machinery with a socket that engages all the various flats of the nut equally to the end that considerable working of the nut can be achieved without in any way marring the finish or the corners of the nut. For this reason it is very desirable to be able to employ a socket wrench. My present socket and the wrenches I have provided for use therewith are such that a socket may be used that operates as the conventional socket operates and which has all the good features of the conventional socket but still can be actually physically put in the operative position and then engaged by a suitable wrench so that the nut can be turned on its threaded bolt or rod.

A principal object of my invention therefore is to provide a new form of socket which is split into two parts along a diameter so that the two parts of the socket may be individually placed around the nut without in any way having any interference with the long bolt or rod to which the nut may be threadedly secured.

A further object of my invention is to provide peripheral engaging means so that the socket can be rotated as is required in turning a threaded nut.

A further object is to provide means for so enclosing my split socket with the wrench employed to turn the same that the socket will have the desirable characteristics of a solid socket.

A further object of my present invention is to provide key means on the surfaces where my two half socket members engage which insures that there will be no endwise displacement of the half socket members when the same are properly put in place on a nut.

Further objects, advantages and capabilities will be apparent from the description and disclosure in the drawings, or may be comprehended or are inherent in the device.

In the drawings:

FIGURE 1 is a perspective view illustrating a preferred form of my socket.

FIGURE 2 is a vertical cross sectional view of one socket and further illustrating one form of wrench used therewith taken as along the line 2—2 of FIGURE 4.

FIGURE 3 is a perspective view illustrating one form of wrench adaptable for use with my improved socket.

2

FIGURE 4 is a fragmentary view partly in section illustrating the head of the wrench as shown in FIGURE 3 and showing the manner in which it engages my socket. In dashed lines certain parts are shown in the position where-
5 in the head of the wrench is opened for engagement with a nut of difficult access.

FIGURE 5 is a fragmentary top plan view of a form of ratchet wrench suitable for use with my sockets.

10 FIGURE 6 illustrates the reverse side of the wrench head shown in FIGURE 5 and shows certain of the parts broken away to better illustrate the internal construction thereof.

15 FIGURE 7 is a perspective view of the socket similar to that shown in FIGURE 1 except that the same is shown in a different sense and partly broken away in section to more clearly illustrate the structure.

FIGURE 8 is a cross sectional view taken along the broken line 8—8 of FIGURE 5.

20 Referring to the drawings, throughout which like reference characters indicate like parts, the numerals 10 and 12 designate the two coacting members which when joined together form my complete socket 13. Each half of the socket as 10 and 12 is semicylindrical in form in that the division line 14 must be an actual diameter if the socket is to be placed in two separate parts around a rod for instance. Endwise alignment of members 10 and 12 is provided for by the key member 16 and the corresponding key-way portion 18. A preferred arrangement is to employ two of these units, one on each side of the socket.
25
30 The interior of my socket is constructed similarly to the usual socket and may, as illustrated, have a hexagonal wall surface as indicated at 20 or this may take on any other conformation common to the type of sockets normally employed. This might conceivably be four sided, eight sided or twelve sided and of course would be made to fit various nut sizes.

35 Referring particularly to FIGURES 1 and 2 of the drawings it will be noted that the upper end of the socket is closed by the transverse wall portions 21 and 21a except for opening 22. This opening should be sufficiently large so that it will admit the largest bolt or rod that would carry a nut the socket could be made to fit. It will be apparent it is believed that my socket will admit of as small an outside dimension as possible for a given socket size. The turning effort of the socket is applied by detents as 24 and 26 which are secured to the interior base of the wrench used. These detents are adapted to fit into openings 28 formed in the vertical wall portion of the socket. In FIGURE 2, it will be noted that openings 28 do not go entirely through the wall, a desirable feature where maximum protection is required for the nuts to be engaged. For many uses, however, openings 28 may be drilled clear through the wall as this is a somewhat cheaper machining operation.

50 55 Detents 24, 26 may be mounted in various types of wrenches. The simplest type of nonratchet type wrench is shown in FIGURES 3 and 4 while a ratchet type is illustrated in FIGURES 5 and 6. It is desirable to point out that the exact form of ratchet forms no part of this present invention as ratchet wrenches of this general type have been made for many years. It is essential for the satisfactory operation of my socket that the two half members 10 and 12 be held in firm engagement with each other, consequently it is important that the nut engaging portion 20 will form an exact fit with the nuts which they are intended to engage.

60 65 In the form shown in FIGURE 3 a substantial handle 32 is provided and at one end a semi-cylindrical socket engaging member 34 is provided. This should be of substantial construction so that detent 24 will be securely positioned and when engaged in opening 28 will be able

to impart the full thrust that can be placed upon handle 32. The outer end of clamp member 34 terminates in a rolled back hinge portion 36 providing an enclosure for the hinge pin 38. Hingedly secured, by hinge pin 38 to clamp member 34, is the movable clamp member 40. This member is also provided with a driving detent 24 and has, extending generally parallel to handle 32, the bifurcated lug 42 having lug members 44 and 46. Pivotably secured within handle 32 as by the short oscillatable shaft 50 is the clamping screw 52. This screw is adapted to operatively receive the wing nut 54 with which a washer 56 is normally employed. The bifurcation between lugs 44 and 46 provides a convenient means for releasing the movable clamping member after the showing of FIGURE 4 and by having reasonable clearance at 60 the socket can be securely clamped in position for use. This form of wrench unit as shown in FIGURES 2, 3 and 4 provides an excellent wrench for use where the bolt extends up through the nut enough so that it is impossible to use the standard socket. There are many such occasions which this form of wrench can serve.

Normally in use the two half members 10 and 12 will be engaged around the nut with the upwardly extending bolt portion or rod passing through hole 22. The two clamp members 34 and 40 can then be secured around the socket when it is in place. Thus the socket can be effectively used even on long rods where neither end is available for passing a single piece socket down the rod onto the nut.

Referring to FIGURES 5 and 6 a handle 62 is provided which has fixedly secured to it the arcuate portion 64 and on the opposite side of the handle the arcuate portion 66. These two portions form one half of the circumference. A movable clamp member 70 is employed which is pivotably secured by hinge pin 72 to the arcuate portion 66. As will be noted in FIGURES 5 and 6 alignable lugs are provided at 74 so that a screw type locking pin may be provided at 76 to hold the arcuate portion 64 and 66 and the movable clamp portion 70 in place to form a cylindrical seat for the ratchet wheel members 80 and 82. In FIGURE 6 one form of ratchet wheel is shown which is provided with saw-tooth type teeth. These are particularly adapted to coact with a two position pawl member 84 which is pivotably mounted at 86 and is further provided with a lug 88 engaged on one or the other side of the spring pressed ball detent 90. Each of these members has an inwardly extending detent similar to the detents 24 and 26 which are indicated at 24a and 26a. Each of the members 80 and 82 are provided with an outwardly extending semi-cylindrical centering rim 92 and 93 adapted to be rotatively engaged by the clamp member 70 and the arcuate members secured to handle 62. This provides for the exact centering of the ratchet wheel, as a unit, coaxially with the cylindrical opening provided at 94.

The form of socket holder shown in FIGURES 5 and 6 has all the virtues of the form shown in FIGURE 3 in addition to providing a two way ratchet controlled by the external lever 96. In operation the two halves of the socket are engaged as before. It is then necessary to engage the two halves 80 and 82 of the ratchet wheel. Next the fixed portions 64 and 66 of the wrench are

engaged which permits the movable clamp member 70 to be swung into the closed position, as shown in FIGURE 5, thus fully enclosing the ratchet wrench portion and securing the socket in operating position. With the two assemblies, the socket and ratchet wheel, disposed on a rod, for instance, they can be passed along the rod until they operatively engage the nut threaded thereto.

It is believed that it will be clearly apparent from the above description and the disclosure in the drawings that 10 the invention comprehends a novel construction of split sockets and wrenches for use therewith.

Having thus disclosed the invention, I claim:

1. A longitudinally split socket and a wrench for use therewith, comprising: two coacting socket members 15 adapted to be joined together to form a nut turning socket; each of said members being semicylindrical in exterior form and being one half of a socket; keying means provided on each of said socket members to assure endwise alignment of said members; each of said members 20 having a multifaced interior surface, generally concave, adapted to form one half of a nut engaging socket; said socket members having a transverse wall, formed one half on each member, and provided with an axially disposed opening of a diameter larger than the bolt size 25 corresponding to the nut size of the socket; radially disposed openings in the cylindrical wall of each member adapted to operatively engage driving means secured to a driving wrench; a driving wrench having a handle and a semicylindrical socket engaging member fixedly secured 30 at one end of said handle and with its axis at right angles to said handle; a semicylindrical movable clamp member hingedly secured at one end to said socket engaging member and means for securing the opposite end adjacent said handle to complete a cylindrical seat for the 35 two socket members; said seat adapted to secure the socket members in fixed relationship to each other and to said handle, and socket driving means secured in said seat and disposed to operatively engage said radially disposed openings in the cylindrical wall of the socket 40 members.

2. The subject matter of claim 1 in which said movable clamp member is provided with a bifurcated lug disposed substantially parallel to said handle when the clamp member is in its closed position; a bolt pivotably secured to said handle and disposed to swing in the same plane as said clamp member and into the bifurcation in said lug and nut means for securing the free end of said clamp member to complete said cylindrical socket seat.
